UNITED STATES PATENT OFFICE.

ABNER WILLIAM SAMUELS, OF NEW YORK, N. Y., ASSIGNOR TO VOGUE MERCHANDISE CO. INC., A CORPORATION OF NEW YORK.

DESIGN FOR A DECORATIVE TOY ANIMAL OR THE LIKE.

Application filed March 10, 1926. Serial No. 16,863. Term of patent 3½ years

To all whom it may concern:

Be it known that I, ABNER W. SAMUELS, a citizen of the United States, and a resident of the city of New York, borough of Manhattan, in the county and State of New York, have invented a new, original, and ornamental Design for Decorative Toy Animals or the like, of which the following is a specification, reference being had to the accompanying drawing, forming part thereof.

The figure is a perspective view of a decorative toy animal, showing my new design.

I claim:

The ornamental design for a decorative toy animal or the like, as shown.

ABNER WILLIAM SAMUELS.
